(57) **CLAIM**

The ornamental design for a deodorizer, as shown and described.

DESCRIPTION

FIG. 1 is a front, right side perspective view of a first embodiment of a deodorizer according to the present design.

FIG. 2 is a front elevation view of the deodorizer shown in FIG. 1, the rear elevation view is identical to the front elevation view.

FIG. 3 is a left side elevation view of the deodorizer shown in FIG. 1.

FIG. 4 is a right side elevation view of the deodorizer shown in FIG. 1.

FIG. 5 is a top plan view of the deodorizer shown in FIG. 1.

FIG. 6 is a bottom plan view of the deodorizer shown in FIG. 1.

FIG. 7 is a front, right side perspective view of a second embodiment of a deodorizer according to the present design.

FIG. 8 is a front elevation view of the deodorizer shown in FIG. 7, the rear elevation view is identical to the front elevation view.

FIG. 9 is a left side elevation view of the deodorizer shown in FIG. 7.

FIG. 10 is a right side elevation view of the deodorizer shown in FIG. 7.

FIG. 11 is a top plan view of the deodorizer shown in FIG. 7.

FIG. 12 is a bottom plan view of the deodorizer shown in FIG. 7.

FIG. 13 is a front, left side perspective view of a third embodiment of a deodorizer according to the present design.

FIG. 14 is a front elevation view of the deodorizer shown in FIG. 13, the rear elevation view is identical to the front elevation view.

FIG. 15 is a left side elevation view of the deodorizer shown in FIG. 13.

FIG. 16 is a right side elevation view of the deodorizer shown in FIG. 13.

FIG. 17 is a top plan view of the deodorizer shown in FIG. 13; and, FIG. 18 is a bottom plan view of the deodorizer shown in FIG. 13.

The broken lines illustrate portions of the embodiment of the deodorizer and form no part of the claimed design.
